UNITED STATES PATENT OFFICE.

EBERHARDT P. NICHOLSON, OF NEW YORK, N. Y.

ARTICULATED DOLL.

1,212,099.

Specification of Letters Patent. Patented Jan. 9, 1917.

Application filed August 23, 1916. Serial No. 116,421.

To all whom it may concern:

Be it known that I, EBERHARDT P. NICHOLSON, a citizen of the United States, and a resident of the city of New York, Richmond Hill, borough of Queens, in the county of Queens and State of New York, have invented a new and Improved Articulated Doll, of which the following is a full, clear, and exact description.

10 My invention relates to dolls of the articulated type and has reference more particularly to the means for controlling the articulation of the doll.

An object of the invention is to provide a 15 simpler and less expensive arrangement whereby the articulation of dolls may be controlled.

A further object of the invention is to provide metallic means which control the articulation of the doll and thereby render the doll more serviceable, which cannot be deteriorated as easily by a sudden pull or by the atmosphere.

A still further object of the invention is to 25 provide an articulated doll which can be easily and quickly assembled.

With the above and other objects in view, the nature of which will more fully appear as the description proceeds, the invention 30 consists in the novel construction, combination and arrangement of parts as herein fully described, illustrated and claimed.

In the accompanying drawings, forming part of the application, similar characters of 35 reference indicate corresponding parts in both views.

Figure 1 is a sectional elevation of a doll embodying my invention; and Fig. 2 is a perspective view of the yielding mechanism 40 by means of which the parts of the doll are articulated.

Referring to the drawings, 3 is a steel blade shaped into a U the sides of which are very long as compared to the base thereof.

45 The extremities of the sides of the U are provided with end slots 4. The base of the U has a central aperture which registers with the central aperture of a leaf spring 5, the ends of which leaf spring are provided with 50 end slots 6. A bolt 7 passes through the registering apertures of the U member and the leaf spring. It also passes through a base block 8 provided at the leaf spring. The torso 9 of the doll has a seat near the bottom 55 of the torso for the base block 8.

Molded within the torso at the seat is a

washer 10 through which the threaded part of the bolt 7 projects and to which the block, leaf spring and U member may be bolted by a nut 11 fitted on to the threads of the bolt 7. 60 The head 12 of the bolt 7 has an eye for engaging the eye of a rod 13. The bolt 7, therefore, firmly locks the U-shaped member and the leaf spring on to the block and the block to the torso 9 of the doll. The torso 9 65 is recessed so that the nut 11 is located slightly below the surface thereof, and also to permit the sealing of the nut after the above-mentioned members have been locked in position. 70

Each slot 6 of the leaf spring faces a bearing for a leg 14 in the torso. The leaf spring is connected to the legs 14 by links 15. The links at the leaf spring are headed to maintain them in engagement with the slots of 75 the spring. The leaf spring is headed at the ends near the slots to prevent the links from slipping out. The links are connected to the legs below the knee by pins 16 passing through the eyes formed in the links thereat. 80 To engage the pins with the links, the leaf spring 5 is depressed through the top opening of the torso 9. This connection of the links 15 with the pins 16 stresses the leaf spring 5 and, therefore, maintains all the 85 joints below the torso tight.

The arms 17 are connected to the U-shaped member by links 18, which links are anchored in the wrist by a pin 19 and connected to the slots 4 by a flexible member or 90 chain 20. The heads 21 of the chains which engage the sides of the U-shaped member are prevented from slipping off by the heading provided at the ends of the sides. The engagement of the chains with the slots 4 95 of the sides of the U is obtained by stressing the sides through the top opening of the torso 9 and bringing the chains into the slots.

The rod 13 has between the ends thereof a 100 spring 22 the normal tendency of which spring is to shorten the length of the rod 13. The rod 13 carries a link 23 on which a yielding ball 24 is provided. The ball 24 serves as a lock for the head 25 of the doll. 105 To force the head over the ball 24 the spring 22 is stressed by pulling the upper eye of the rod 13 out of the torso through the upper opening thereof and passing a wire across the eye to prevent the spring 22 from pulling the rod 13 into the torso. The head 25 110 of the doll is then forced on to the ball 24.

The ball being of yielding material, the head will pass thereover and the ball will expand, the pressure required for passing the ball into the head being considerable as compared to what the pressure may be for articulating the head or when pulled by a child. By withdrawing the wire which prevents the spring 22 from drawing the rod 13 into the torso, the spring is allowed to draw the head against its seat, as clearly shown in the drawing.

From the above description it will be seen that in the disclosed doll the articulated parts are actuated not through elastic members as is common but by metallic springs, which give a more permanent article and which can be manufactured more cheaply and assembled easily.

I claim:

20 1. A doll having an articulated body, a leaf spring within the torso of the doll, links connecting the leaf spring to the legs at the knees, a blade having the shape of a U the sides of which are elongated resting 25 with its base on the leaf spring, means securing the U-shaped blade to the leaf spring and the torso, and links connecting the extremities of the U-shaped blade to the wrists.

30 2. A doll having an articulated body, a leaf spring within the torso of the doll, means anchoring the leaf spring to the torso, links connecting the leaf spring to the legs at the knees, said means adapted to maintain said leaf spring stressed, a U-shaped 35 spring rising from the leaf spring and anchoring therewith, and means connecting the ends of the U-shaped spring to the remote members of the arms, said means adapted to maintain said U-shaped spring stressed.

40 3. A doll, comprising a torso, articulated arms associated with the torso, articulated legs also associated with the torso, a leaf spring, means anchoring the leaf spring 45 within the torso in proximity of the juncture of the torso with the legs, a U-shaped spring rising from the leaf spring toward the top of the torso, the U-shaped spring

being anchored to said leaf spring with the base thereof, links connecting the leaf spring to the legs at the knees, said connection maintaining the leaf spring stressed, links connecting the wrists of the sectional arms to the ends of the U spring, said connection stressing the U-shaped spring, an expansive rod anchored with one end thereof to the torso, a ball associated with the other end of said rod, and a head carrying said ball and engaging the torso, said expansive rod normally maintaining the head against the torso.

4. A doll having a torso, articulated legs associated with the torso, articulated arms associated with the torso, a leaf spring, said torso presenting a seat for the leaf spring 65 in proximity of the juncture thereof with the legs, a U-shaped spring resting with its base on the leaf spring and having the ends thereof directed toward the top of the torso, means anchoring the U-shaped spring and 70 the leaf spring to the torso, a rod having one end thereof anchored to the means anchoring the leaf to the U-shaped spring, a spring associated with said rod and normally tending to resist the lengthening 75 thereof, a ball associated with said rod, a head carrying said ball whereby said head is drawn against the torso by said spring which resists the lengthening of the rod, flexible members connecting the wrists of 80 the articulated arms with the ends of the U-shaped springs and whereby the joints of said articulated arms are maintained in engagement, and flexible means connecting the ends of the leaf spring to the articulated 85 legs in proximity of the knees.

5. A doll having an articulated body, a flat metallic spring within the torso of the doll, flexible members connecting the spring to the legs, a second flat spring, flexible means connecting the second flat spring to the arms, means anchoring the two springs to the torso, a yielding member in the head of the doll, and a yielding rod connecting the yielding member to the torso.

EBERHARDT P. NICHOLSON.
